IMPROVEMENT IN WATER ELEVATORS.

ISAAC A. PINNELL, OF GALVA, ILLINOIS.

Letters Patent No. 60,239, dated December 4, 1866.

SPECIFICATION.

TO ALL WHOM IT MAY CONCERN:

Be it known that I, ISAAC A. PINNELL, of Galva, in the county of Henry, and State of Illinois, have invented a new and improved Water Elevator; and I do hereby declare that the following is a full, clear, and exact description thereof, reference being had to the accompanying drawings, forming part of this specification.

The nature of my invention consists in providing machinery to elevate water from common wells in such a manner that one or more buckets may be used at the same time. When two are used while one bucket is descending, the other is ascending to the top of the well.

It more particularly consists in constructing a lever in combination with gear-wheels, that by means of the said lever the wheels may be thrown in and out of gear, as may be desired, so that either of the buckets may be elevated and lowered at will.

Figure 1 is a top plan view of my improved water elevator.

Figure 2 is a vertical sectional elevation, from the line *z z*.

Figure 3 is a transverse sectional elevation, from the line *y y*.

To enable others skilled in the art to make and use my invention, I will proceed to describe its construction and operation.

Letters of like name and kind refer to like parts in each of the figures.

A represents the curb of a well of ordinary construction, which is placed around the top of a well. B is a large wheel provided with ratchet teeth upon the periphery, in which a pawl, C, works. Upon the inner side of the rim of the said wheel B are also ratchet teeth, which are made to fit and mesh into corresponding teeth upon the pinion-wheels D D'. The said pinions are secured to the shaft of the drums E E' upon the opposite end of which are gear-wheels F F', which mesh in corresponding teeth with each other. The shafts of the drums E E' have journals which run in suitable bearings, G, the said bearings being secured to the top of the curb A. H is a cross-timber running transversely from side to side of the curb A, and to which is secured one of the hangers bearing one end of the shaft of the ratchet-wheel B. I is a friction-roller, over which the rope J passes to keep the bucket in its proper position as it is ascending and descending. This roller, I, is provided with journals that run in bearings K K, which are also secured to the top of the curb. L L' are the buckets attached to the ends of ropes J and M, which ropes serve the purpose of elevating and lowering the buckets into and out of the well. N is a lever having its fulcrum at O, fig. 2, and being provided with an arm, R, that extends upward from the fulcrum. At the upper end of the said arm is a slot, (as seen in dotted lines in fig. 2,) which is made to fit in a corresponding lug which projects from the bar P. The bar P is also provided with arms, Q Q, at each end, which extend upward and in the upper ends of which are also slots that fit to the bearing of the shafts of the drums E E'. At the end of the bar or lever N is a guide bar or staple, in which the end of the lever N works. The operation is simple and easy. When it is desired to lower the bucket L' into the well, the end of the lever N is raised, as shown in red lines, fig. 2, which movement disengages the pinion D' from the main wheel B, then by the action of the gear-wheel F, upon the wheel F', the bucket L' is lowered, and the bucket L is raised. When it is desired to lower the bucket L, the lever N is brought down to the position, as shown in fig. 2, which depression disengages the pinion D from the wheel B, and at the same time engages the pinion D' with the wheel B. When by the action of the gear-wheel F' upon the wheel F the bucket upon the end of the rope M descends at the same time the bucket L' ascends. It will here be observed that in the operation of raising and lowering the buckets L and L', and as the end of the lever N is raised, as seen in red lines, that the slotted bar R, which extends upward, is engaged with the lug upon the bar P. At the same time the slotted projections Q Q upon the ends of the bar P are engaged, respectively, with the ends of the respective shafts of the drums E E, so that by moving the lever F up and down the ratchet-pinions D D' are engaged and disengaged, respectively, with the ratchet upon the inside of the rim of the wheel B, by which means the buckets are made to descend and ascend, as may be desired. It will also be observed that in the bottom of the buckets are valves, A² A², which open as soon as the bottom of the bucket strikes the water, the bucket then becomes filled. By raising the bucket by the weight of water therein the valve is at once closed by the weight of the water in the bucket, and the water is retained until the bucket reaches the top, when the hooks on the side of the bucket come in contact with a bail, B², running across the inside of the curb, and by still raising the bucket it is emptied into the spout C², which conducts the water into any proper receptacle. A brake of any ordinary form may be applied to pulley D² upon the end of the shaft of the drum E. Thus it will be seen that by my device water may be drawn

from wells easily and rapidly by adjusting the lever N, as desired, and turning the wheel B by means of the crank O². The buckets may be made to rest at any point in the well by the pawl C, engaging in the ratchet-wheel B.

Having thus described my invention, what I claim as new, and desire to secure by Letters Patent, is—

1. The bar P provided at the ends with slotted arms that engage the shafts of the drums E E', for the purposes and substantially as described.
2. The bar P provided with the slotted arms Q Q in combination with the lever N, substantially as and for the purposes herein described.
3. In combination with the bar P and lever N, the drums E E', with the gear-wheels F F' and the ratchet-wheels D D', for the purposes and substantially as described.
4. The wheel B provided with a ratchet upon its periphery, and one upon the inside of the rim in combination with the drums E E', lever N and bar P, substantially as herein set forth.

ISAAC A. PINNELL.
